CLAIM

The ornamental design for a Y-type three way single-valve pipe connector, as shown and described.

DESCRIPTION

FIG. 1 is a top view of a Y-type three way single-valve pipe connector showing my new design;

FIG. 2 is a front view thereof;

FIG. 3 is a rear view thereof;

FIG. 4 is a left side view thereof, the right side being an identical mirror image;

FIG. 5 is a bottom view thereof;

FIG. 6 is a perspective view thereof; and,

FIG. 7 is a top view of a Y-type three way single-valve connector according to the present invention.

The second embodiment as shown in FIG. 7 has sides, top and bottom identical to that shown in FIGS. 1 through 6 with the only difference being in the Y-type three way single-valve connector elements.
